UNITED STATES PATENT OFFICE

HARRY F. ABRAMS, OF GARDEN CITY, AND EDWIN G. INTO, OF NEW YORK, N. Y., ASSIGNEES TO VACUUM OIL COMPANY, OF NEW YORK, N. Y., A CORPORATION OF NEW YORK

RECEPTACLE FOR PETROLEUM AND THE LIKE

Application filed October 8, 1928. Serial No. 311,058.

This invention relates to a receptacle in the form of a drum or barrel, for use in dispensing products such as heavy petroleum oil, petrolatum and the like. The object of the invention is to provide a receptacle, for the purpose in question, with simple and effective means for heating the contents of the receptacle to permit such contents to be withdrawn in liquid form under conditions of temperature in which the contents would otherwise be solid or too viscous to flow readily.

The heating means in question have the form of a tubular conduit or pipe fixed within the receptacle and adapted for connection with an external source of a fluid heating medium, such as steam or hot water, and the invention resides in the particular form of such conduit and its relation to the discharge orifice of the receptacle, whereby the desired result is secured in the simplest manner and with the occupancy of a minimum space by the conduit. The invention comprises also convenient and effective means for attaching the ends of the conduit to the walls of the receptacle in such a way as to avoid leakage of the contents at such points of attachment.

In the drawings:

Figs. 1 and 2 are, respectively, a plan view and a side elevation of a sheet-metal drum or barrel provided with heating means embodying the present invention;

Fig. 3 is a sectional view on the line 3—3 in Fig 1 and on a larger scale; and

Figs. 4 and 5 are sectional detail views of the inlet and outlet ends respectively of the heating conduit, together with the means by which these ends are attached to the walls of the drum.

The invention is illustrated as applied to a sheet-metal drum 1 of ordinary form, having cylindrical side walls and flat end walls or heads. The upper head has the usual large filling opening, closed by a cap 2. For the withdrawal of the contents, the drum is provided, in its side wall, adjacent the lower head, with an outlet opening or spud closed by a plug 3. When the contents of the receptacle are fluid, they may be withdrawn

through this outlet opening with the drum either standing upright, as in Fig. 3, or lying horizontally, with the outlet opening at the bottom.

The heating conduit in which the invention is particularly embodied comprises a pipe 4, bent so as to have two limbs at a right angle with each other. One end of this pipe is connected with an opening in the upper end of the drum, while the other end is connected with an opening in the side wall near the lower head, as shown in Fig. 3. One of the limbs of the pipe, therefore, extends vertically from the top nearly to the bottom of the receptacle, while the other limb extends horizontally across the bottom of the receptacle. Preferably, the heating conduit and the outlet opening are arranged to lie in the same plane.

The form and arrangement of the heating conduit is such as to insure sufficient heating and effective discharge of the contents of the drum. It will be evident that in withdrawing the contents it is desirable, at the outset and throughout the operation, to heat and melt the contents at the bottom and adjacent the outlet opening. This result is immediately effected by the horizontal limb of the conduit extending across the bottom. It is necessary, further, that as the contents at the bottom are withdrawn, the superincumbent contents shall flow and descend, and this result is secured by the vertical limb of the conduit extending from the bottom to the top of the receptacle. It should be noted that, in either the upright or horizontal position of the receptacle, there is a horizontal limb along the lowermost portion or bottom and a vertical limb extending from the bottom to the uppermost portion or top, and that these limbs converge and communicate at the interior angle adjacent the outlet opening.

In order that the heating conduit or pipe may be conveniently and securely attached to the walls of the drum, the construction shown particularly in Figs. 4 and 5 is used. As shown in Fig. 4, this construction includes a bushing 6 having internal and external threaded cylindrical surfaces, this bushing having an outwardly extending flange at its

outer end and an inwardly extending flange at its inner end. A nut 9 is screwed on the external threaded surface to clamp the bushing in place in an opening in the head of the drum, and a gasket 7, interposed between the head and the outer flange of the bushing, provides a fluid-tight seal at this joint. The upper end of the heater pipe 4 extends into the bushing and is flanged at its extremity, and a gasket 8 is interposed between the pipe flange and the inwardly projecting flange at the inner end of the bushing. A plug 5, screwed into the bushing 6, presses the end flange of the pipe against the gasket 8. The plug 5 is perforated and screw-threaded, for convenient connection with a hose or pipe through which the heating medium may be introduced.

The outlet end of the heating pipe is joined with the side wall of the drum by a construction substantially similar to that just described and including a bushing 10, a nut 14 and a sealing gasket 13 interposed between the bushing and the wall of the drum. In this case, however, a gland nut 11 is substituted for the plug 5 and arranged to compress a packing 12 around the end of the heating pipe.

The invention claimed is:

- 30 1. In a receptacle for petroleum and the like, the combination, with a generally cylindrical shell provided with an opening, for the discharge of its contents, adjacent the angle between the side wall and an end wall of the shell, of a tubular conduit, for the passage of externally supplied heating fluid, enclosed within the shell and bent to approximately right-angle form, the limbs of said conduit being substantially parallel, respectively, with said end wall and side wall.
- 35 2. In a receptacle for petroleum and the like, the combination, with a shell provided with two openings in the walls thereof, of a tubular conduit, for the passage of externally supplied heating fluid, extending, within said shell, from one of said openings to the other, and means, for making a fluid-tight joint between each end of said conduit and the adjacent wall of the shell, comprising a bushing having internal and external threaded cylindrical surfaces, an outwardly-extending flange at its outer end and an inwardly-extending flange at its inner end, a nut screwed on said external threaded surface and operating, with said outwardly-extending flange, to fix the bushing in the wall of the shell, an externally threaded and centrally bored member screwed into the bushing and engaging the end of said conduit, and packing surrounding the end of the conduit and compressed between said member and said inwardly extending flange on the bushing.
